UNITED STATES PATENT OFFICE.

FRANKLIN H. HART, OF NEW HAVEN, CONNECTICUT, ASSIGNOR TO C. COWLES AND COMPANY, OF NEW HAVEN, CONNECTICUT, A CORPORATION OF CONNECTICUT.

CURTAIN ROLLER.

Application filed September 19, 1921. Serial No. 501,533.

To all whom it may concern:

Be it known that I, FRANKLIN H. HART, a citizen of the United States, residing at New Haven, county of New Haven, State of Connecticut, have invented an Improvement in Curtain Rollers, of which the following is a specification.

This invention relates to curtain or shade rollers and has for an object to provide 10 an improved curtain roller in which the pawls will be held against rattling.

It is a further object of the invention to provide a curtain roller having the usual pair of pawls pivoted on the rotating portion of the roller adapted to coat with a recess in the stationary element to hold the roller against turning, in which means is provided, operated by the holding pawl, for preventing rattling of the free pawl.

20 With these and other objects in view I have devised the structures disclosed in the accompanying drawing in which,

25 Fig. 1 is a front elevation of my improved roller showing a curtain or shade in position thereon.

Fig. 2 is an end view of same.

Fig. 3 is a longitudinal sectional view at the pawl end of the roller on a somewhat enlarged scale.

30 Fig. 4 is an end view of the form shown in Figs. 1 to 3 also on an enlarged scale.

Fig. 5 is a similar view of a slightly modified form, and

35 Fig. 6 is a similar view of a still further modified form.

The roller comprises the usual stationary element 10 and the rotating element 11 forming the usual spool on which the curtain 12 is wound. The stationary element 10 is secured at its opposite ends in brackets 13 which are adapted for attachment at the top or any portion of the window by suitable screws 14. In the present instance this stationary element is a cylindrical rod fastened 45 by any suitable means such as a pin 15 in recesses in the brackets 13. This rod or a boss on the bracket is provided with a recess 16 which, when the roller is placed in position, is on the top of the stationary element, as shown in the drawing. The rotating shell 11 is closed at its opposite ends by suitable discs 17 to one of which discs are pivoted by suitable rivets 18, a pair of pawls 19, so that these pawls are carried about the stationary member as the shell rotates in wind-

ing and unwinding the curtain in the usual manner. A coiled spring 20 is provided within the roller tending to rotate the shell in the direction of the arrows to wind up the curtain. Each pawl is provided on its 60 inner side with a projecting lug 21 which is adapted, when the shell is rotated, to seat in the recess 16 and hold the shell against turning as is usual in this class of devices. Each pawl is, however, provided with a 65 curved projection 22 of sufficient length that when the lug 21 of one pawl is within the recess 16, the end thereof will press against a short projection 23 on the other or free pawl on the opposite side of its pivot, and 70 tend to turn said free pawl about its pivot 18 and hold it against any suitable part of the rotating element, such as the flange 24. The pawls are pivoted on the disc 17, a sufficient 75 distance from their center of rotation, that the reaction of the holding shoulder 25 of the recess 16 pressing on the lug 21 of the pawl tends to rotate the pawl counterclockwise, as viewed in Fig. 4. This presses the end of the long projection 22 against the 80 side of the short projection 23 on the free pawl tending to turn it clockwise, as viewed in Fig. 4, on its pivot 18 and hold it in contact with the flange 24. The pawl may be so shaped that the curve of the projection 22 85 rests against this flange or there may be provided a second lug 26 to contact with the flange. It will, therefore, be noted that the pressure of the spring tending to rotate the shell of the roller acting through the holding 90 pawl retains the free pawl against rattling. This is particularly desirable in curtain rollers which are to be used on automobiles.

In Fig. 5 I have shown a slight modification in which the free end of the curved projection 22 does not press against the side of the short projection on the other pawl but the side 27 of this projection presses against a short projection 23' on the other pawl 95 tending to turn it about its pivot 18 into contact with the flange 24 in the same manner as that disclosed in Fig. 4.

In Fig. 6 the short projection 28, corresponding to short projections 23 and 23' in Figs. 4 and 5, is located on the opposite side 100 of the pivot 18 and the long curved projection 22' contacts with a side of this lug 105 to turn the free pawl counterclockwise or inwardly toward the stationary element and to rest thereagainst. The effect, however, is 110

the same as in the other two forms, as under the action of the spring 20 through the holding pawl the free pawl is pressed against the three points of support and prevented from rattling.

It will be noted, from an inspection of the drawing, that the device is very simple in construction and that there is no change necessary in the roller itself to accomplish the desired result of preventing rattling of the loose pawl, the change being in the pawls themselves. It will also be apparent that the pawls may be very freely pivoted on their pivots 18 so that they are free to turn in the rotation of the element 11, but that when the lug 21 in one of them is in the recess 16 of the stationary element to prevent turning of the element 11 the free pawl is positively prevented from rattling.

Having thus set forth the nature of my invention, what I claim is:

1. A curtain roller comprising rotary and stationary elements, means tending to turn the rotary element, a pair of pawls carried by the rotary element, said pawls and stationary element being provided with shoulders adapted to coact to prevent turning of the rotary element in one direction, and means operated by the holding pawl acting on the free pawl to prevent its rattling.

2. A curtain roller comprising stationary and rotary elements, means tending to rotate the rotary element, a pair of pawls pivoted to the rotary element, the pawls and stationary element being provided with shoulders adapted to coact to hold the rotary element against turning in one direction, and means carried by the pawls adapted when one pawl is in holding position to engage the other pawl and hold it against rattling.

3. A curtain roller comprising stationary and rotary elements, means tending to rotate the rotary element, a pair of pawls pivoted to the rotary element, said stationary element being provided with a recess, lugs on the pawls adapted to enter said recess, and means on the pawls adapted when a pawl is in holding position to retain the other pawl against rattling.

4. A curtain roller comprising stationary and rotary elements, means tending to rotate the rotary element, a pair of pawls pivoted to the stationary element, said stationary element being provided with a recess, lugs on the pawls adapted to enter the recess to prevent turning of the rotary element in one direction, and a projection on each pawl adapted when a pawl is in holding position to press against the free pawl and hold it against rattling.

5. A curtain roller comprising stationary and rotary elements, means tending to rotate

the rotary element, a pair of pawls pivoted to the rotary element, coacting means on the pawls and stationary element to hold the rotary element against rotation in one direction, and means operated by the rotating means to hold the free pawl against rattling.

6. A curtain roller comprising stationary and rotary elements, means tending to rotate the rotary element, a pair of pawls pivoted to the rotary element, the pawls and stationary element being provided with shoulders adapted to coact to hold the rotary element against turning in one direction, projections on the pawls on opposite sides of their pivots, the projection of one pawl when the pawl is in holding position adapted to contact with the opposite projection of the other pawl and tend to turn it on its pivot.

7. A curtain roller comprising rotary and stationary elements, means tending to rotate the rotary element in one direction, a plurality of separate relatively movable pawls carried by the rotary element and provided with shoulders, said stationary element being provided with a shoulder adapted to coact with the shoulder on any of the pawls to prevent turning of the element under the action of said means, and means carried by each pawl adapted when the pawl is in holding position to engage the adjacent free pawl and retain the same stationary to prevent rattling thereof.

8. A curtain roller comprising rotary and stationary elements, means tending to rotate the rotary element in one direction, a pair of pawls pivoted to the rotary element and each provided with a shoulder, said stationary element being provided with a shoulder adapted to engage the shoulder on either of the pawls to retain the rotary element against turning in the opposite direction, and a projection carried by each pawl adapted when the pawl is in holding position to be pressed against the free pawl under the action of the turning means to hold the free pawl stationary and prevent rattling thereof.

9. A curtain roller comprising rotary and stationary elements, means tending to rotate the rotary element in one direction, and a pair of separate relatively movable pawls carried by one of said elements, said pawls and the other element being provided with coacting means to hold the rotary element against rotation under the action of said first mentioned means, each pawl being adapted when in holding position to transfer pressure under action of the element rotating means to the other pawl and hold it against rattling.

In testimony whereof I affix my signature.

FRANKLIN H. HART.
